UNITED STATES PATENT OFFICE.

ALBERT HAUSSMANN, OF FOND DU LAC, WISCONSIN.

TOOTH-BRUSH.

SPECIFICATION forming part of Letters Patent No. 715,263, dated December 9, 1902.

Application filed April 1, 1901. Serial No. 53,752. (No model.)

To all whom it may concern:

Be it known that I, ALBERT HAUSSMANN, a citizen of the United States, and a resident of Fond du Lac, in the county of Fond du Lac and State of Wisconsin, have invented certain new and useful Improvements in Tooth-Brushes; and I do hereby declare that the following is a full, clear, and exact description thereof.

10 My invention relates to tooth-brushes designed to brush the outer and inner surfaces of the teeth at the same time; and it consists in certain peculiarities of construction and combination of parts, as will be fully set forth 15 hereinafter in connection with the accompanying drawings and subsequently claimed.

In the said drawings, Figure 1 is a front elevation of a tooth-brush embodying my invention, and Fig. 2 is a side elevation of the 20 same.

Referring to the drawings, *a* represents the handle proper of the device made of any suitable material—such as bone, ivory, wood, metal, hard rubber, or other composition—25 and secured thereto, as by pins, screws, or rivets *b b*, are the shanks *c c*, preferably flat strips of spring metal, of the brush-holders *d d*, said shanks *c* beyond the end of the handle *a* being curved outwardly in opposite directions, and thence rearwardly and finally forwardly, as shown at *e*, and permanently secured, as by soldering or otherwise, to the brush-holders *d*.

The brush-holders *d* are preferably formed 35 of flat metallic plates having spring-tongues *ff* projecting from their upper, lower, and side edges, as shown, and curved or inwardly inclined, so as to securely hold the brush-backs *g*, which are held in place by being 40 slipped or snapped past said tongues. The edges of the brush-backs are suitably curved or inclined for engagement with said correspondingly-bent tongues, and the outer or opposed faces of said brush-backs are each 45 further preferably curved on the arc of an ellipse and provided with any suitable brushing devices, such as the rows of bristles *h h* shown.

With my device should the bristles or other 50 bushing material become worn out the brush-

backs can be removed and replaced by new brushes or brush-backs may be provided in interchangeable series having brushes of different degrees of stiffness or softness to be used as required, one handle and pair of 55 spring-shanks serving for any of the same, this being a matter of considerable advantage, as where a silver or other expensive handle is employed.

The opposing pair of brushes are arranged 60 in longitudinal planes slightly oblique to the longitudinal plane of the handle, and the ends of the shanks *c* beyond the handle *a* are outwardly curved in opposite directions, and then each shank end is further rearwardly 65 and then forwardly curved, as shown and described, the object being to permit the brushes to be brought closely together, so as to clean both sides of the teeth at once, and at the same time by reason of the described oblique 70 arrangement of the brushes relative to the handle and the described peculiar curving of the shanks to prevent unpleasant contact between the shanks and the lips and mouth of the user.

Having thus described my invention, what I claim as new, and desire to secure by Letters Patent, is—

A tooth-brush comprising a handle, oppositely-disposed substantially oblong brushes 80 arranged in longitudinal planes, slightly oblique to the longitudinal plane of the handle, and means for connecting said brushes to one end of the handle comprising yieldable arms each fastened at one end to the handle 85 and at the other end to one of the brushes, said arms being curved in opposite directions to separate the same and both curved rearwardly in the same direction from the handle and thence forwardly to their points 90 of connection with the brushes substantially as described.

In testimony that I claim the foregoing I have hereunto set my hand, at Fond du Lac, in the county of Fond du Lac and State of 95 Wisconsin, in the presence of two witnesses.

ALBERT HAUSSMANN.
